UNITED STATES PATENT OFFICE

2,438,384

TOILET STOOL

Albert M. Broudy, Pittsburgh, Pa., assignor of
one-half to James R. Snyder, Wilkinsburg, Pa.

Application April 18, 1945, Serial No. 589,042

2 Claims. (Cl. 155—31)

1

This invention relates to a toilet tool for infants, and important objects and advantages of the invention are to provide a stool of the character described, which will comfortably and safely accommodate an infant and quickly acquaint and train the latter as to its use and purpose, which constitutes a small bench and when employed as such gives no obvious suggestion as to its actual toilet purposes, which embodies means for preventing an infant seated therein from accidentally falling therefrom, which is simple in its construction and arrangement, sanitary, compact, durable and efficient in its use, and comparatively economical in its manufacture.

With the foregoing and other objects in view which will appear as the description proceeds, the invention resides in the novel construction, combination, and arrangement of parts herein specifically described and illustrated in the accompanying drawing, but it is to be understood that changes in the form, proportions, and details of construction may be resorted to that come within the scope of the claims hereunto appended.

In the drawing wherein like numerals of reference designate corresponding parts throughout the several views:

Figure 1 is a front elevational view of the improved toilet stool in the upright position.

Figure 2 is a side elevational view thereof.

Figure 3 is a side elevational view, partly in section, of the stool in overturned position, with the parts thereof arranged for toilet purposes.

Figure 4 is a rear elevational view, partly in section, of the toilet seat, embodied in the present invention.

Figure 5 is a bottom end view of the toilet seat.

Referring in detail to the drawing, the improved stool comprises a flat, oblong, rectangularly-shaped top 1, which is supported by a pair of flat, upwardly tapering, supporting legs 2. The legs are fixedly secured in position adjacent to respective ends of the top 1, and slightly converge toward the upper ends thereof. The lower ends of the legs 2 are recessed, as at 3, to more readily adapt same to surfaces upon which the stool may be positioned.

A toilet seat 4 is fixedly secured in position between the supporting legs 2 beneath the top 1. The toilet seat is disposed vertically edgewise at right angles with respect to the top 1, and serves to brace the legs and top to provide a substantial and sturdy stool structure. The top 1, legs 2, and toilet seat 4 are all rigidly secured to

2

gether by means of screws 5, or by any other suitable securing elements.

The toilet seat 4 is provided with a comparatively large seat opening 6, which is semi-circular at its upper end and open at its lower end. The lower edge margin of the toilet seat is reduced in length to form a pair of depending bearing members 7, which are disposed at respective sides of the seat opening 6 at the open lower end of the latter.

A closure panel 8 is hingedly mounted in the seat opening 6 by having the lower ends of its side edges pivotally engaged by a pair of pivoting pins 9, which latter are fixed in respective bearing members 7 and extend horizontally. The closure panel is generally shaped to conform to the contour of the seat opening 6, except that each side edge thereof is provided with a large recess 10, which is disposed in the lower portion of said closure panel.

A stop plate 11 is secured against the rear face of the toilet seat 4 and depends into the seat opening 6 to engage the closure panel and thereby limit and prevent the movement of the latter, on its pivotal connection, from the seat opening 6 in the rearward direction.

A latching element 12 is pivotally connected against the front face of the toilet seat 4, and is frictionally adjustable to overlap and engage the top of the front face of the closure panel 8 for holding the latter in the seat opening 6 against the stop plate 11, as clearly shown in Figures 1 and 2.

A large flat sanitary shield 13, constructed of plastic composition or any other suitable sheet material, is secured against the rear face of the closure panel 8, for the obvious purpose of protecting the latter against moisture absorption when the device is employed for toilet purposes in the manner to be described.

A holding bar 14 is secured against the lower free ends of the bearing members 7 by a pair of screws 15. The screws 15 are of considerable length and not only serve to secure the holding bar in position, but also secure the pivoting pins 9 in the respective bearing members and greatly reinforce the latter.

When the closure panel 8 is held in the closed position in the seat opening 6 by the latching element 12, the stool, in its upright position, may be conveniently employed by adults as a footstool, or as a step for reaching elevations beyond normal reach, or such closed stool may be used by children as a play table, stand, or seat. By overturning the stool upon its side with the clo-

sure panel in the closed position, said stool provides a low chair structure readily adaptable for seating an infant or small child.

To employ the stool for toilet purposes, the stool is overturned upon its side with the front thereof being disposed upwardly. The latching element 12 is released to allow the closure panel to be shifted, on its pivotal connection, to the vertical position at right angles to the now horizontal position of the toilet seat 4, as shown in Figure 3.

The holding bar 14 is provided to prevent shifting of the closure panel 8 beyond its right-angled position with respect to the toilet seat 4. The lower front edge corner of the closure panel is rounded, as at 16, to provide the necessary clearance to allow the shifting of the closure guard to its rightangular position against the holding bar.

In practice, a suitable receptacle is intended to be placed beneath the toilet seat 4 of the overturned stool, and the infant is seated upon the toilet seat with the closure panel disposed upwardly between his legs. The recesses 10 provide ample clearances for the passage of the legs. The closure panel and portions of the top 4 and legs 2 surround the seated infant and safely support him during toilet procedures.

The present invention provides a most efficient device of its kind, which may be economically constructed, and conveniently employed for providing early training toilet services for infants in the manner herein set forth.

What I claim is:

1. A toilet stool comprising a pair of supporting legs, an oblong rectangularly-shaped top mounted on said legs, a toilet seat secured in the vertically edgewise position between said legs and beneath said top and being provided with a seat opening, said opening being open at its lower end, a closure panel mounted in said opening for closing the latter and having the lower end thereof pivotally connected with the lower end of said seat, means for preventing the shifting of said closure panel in the rearward direction from said opening, means for securing said closure panel in said opening, and means for preventing the shifting of said closure panel in the forward di-

rection beyond a position at right angles with respect to said seat.

2. A toilet stool of the character described, comprising the combination of a pair of supporting legs, an oblong rectangularly-shaped top mounted on said legs, a toilet seat secured in the vertically edgewise position between said pair of legs and beneath said top, said toilet seat being provided with a seat opening that is open at its lower end, the lower end of said toilet seat being formed to provide a pair of depending bearing members, a closure panel mounted in said opening, a pair of pivoting pins fixed in respective bearing members and engaging said closure panel for pivotally connecting the latter to said toilet seat, a stop plate secured against the rear face of said toilet seat and depending into said opening for preventing the shifting of said closure panel in the rearward direction from said opening, a latching element mounted on the front face of said toilet seat and being adjustable for securing said closure panel in said opening, a holding bar mounted against said bearing members for preventing the shifting of said closure panel in the forward direction beyond a position at right angles with respect to said toilet seat, said closure panel having recessed side edges to provide clearances when said closure panel is in said rightangular position, means for securing said holding bar in position against said bearing members and for reenforcing the latter, and a sanitary shield mounted against the rear face of said closure panel.
